MAGNETRON HAVING WAVE-GUIDE OUTPUT

Johannes Antonius Van de Goor and Karl Walter Hinkel, Eindhoven, Netherlands, assignors to North American Philips Company, Inc., New York, N.Y., a corporation of Delaware

Application March 18, 1958, Serial No. 722,237

Claims priority, application Netherlands March 30, 1957

2 Claims. (Cl. 315—39)

This invention relates to a magnetron having a wave-guide output for connection to a wave-guide of rectangular cross-section, in which, starting from a slit-shaped aperture in one of the resonant cavities within a wave-guide of circular cross-section, two opposed wall portions diverge in the direction of the glass window at the end of the wave-guide.

In the known magnetrons of the above-mentioned kind, the window is mounted in a dished cover which together with a rim soldered to the end of the wave-guide produces a filter slit which extends at right-angles to the wave-guide axis. The connecting flange having a rectangular aperture is soldered to the magnetron by means of a conductive cylinder the diameter of which is larger than the dished closing member of the wave-guide. This construction is comparatively bulky and its manufacture is relatively expensive.

Magnetrons are also known in which two diverging wall parts in a wave-guide are used and in which both the wave-guide output and the wave-guide to be connected thereto have either circular or rectangular cross-sections. The circular cross-section has a limitation in that a transition to the rectangular cross-section is still required, while the rectangular shape suffers from the disadvantage that it requires a comparatively expensive construction in view of the connection to the anode block of the magnetron.

Magnetrons are also known in which the diverging wall parts extend in a wave-guide having two parallel walls to which two semi-circular walls of gradually increasing size are joined. However, such a construction is very expensive.

It is an object of the present invention to provide a construction of the kind described in the opening part which can be cheaply manufactured and has a very small size.

According to the invention, in a magnetron having a wave-guide output suited for connection to a wave-guide having rectangular cross-section in which, starting from a slit-shaped aperture in one of the resonant cavities in a wave-guide of circular cross-section, two opposed wall parts diverge from the aperture in the direction of the glass window at the end of the wave-guide, the glass window is mounted in a flat connecting flange which with the aid of a conductive cylinder is secured to the magnetron casing so that between this conductive cylinder and the outer surface of the wave-guide, which extends closely up to the flange, a narrow filter slit is left the bottom of which is spaced away from the flange by a distance of from one quarter to one half of the operating wave-length.

In order that the invention may readily be carried out, one embodiment thereof will now be described, by way of example, with reference to the accompanying drawings, in which—

Fig. 1 is a sectional view taken in the plane passing through the axes of the wave-guide and the magnetron, and

2

Fig. 2 is a sectional view taken in a plane passing through the axis of the wave-guide at right angles to the axis of magnetron.

The magnetron parts which are not essential to the invention are shown diagrammatically only.

In the figures, reference numeral 1 designates the anode block of the magnetron having fin-shaped anode segments 2. A laterally extending conical wave-guide 3 is bored in the magnetron, two segments 4, which start from a narrow aperture 5 in one of the resonant cavities of the magnetron, extending in the direction of the glass window 6 which is sealed in a flat flange 7. The flange 7 is soldered to the anode block by means of a conductive cylinder 8 so that a slit 9 is left between the cylinder 8 and the wave-guide. To the flange 7 there is directly connected a flange 10 of a rectangular wave-guide 11 having a smaller transverse dimension *a* and a larger transverse dimension *b*. The flange 10 is provided with a continuous annular filter slit 12 the depth of which is about one quarter of the operating wave-length. The output coupling described has a small length and its manufacture is comparatively cheap since the conical wave-guide can be bored directly in the anode block.

What is claimed is:

25 1. A magnetron comprising a hollow anode block having a plurality of fin-shaped anode segments defining a plurality of resonant cavities in said block, said block having an outward flaring bore defining a conical wave-guide connected to one of said resonant cavities by an aperture in said anode block, a hollow electrically conducting cylinder surrounding the conical bore and secured at one end to said anode block and defining with said anode block a slit between said cylinder and said wave-guide, a flange having a window therein for the transmission of electromagnetic waves secured at the other end to said electrically conducting cylinder, and a rectangular wave-guide having a flange at one end connected to the first-named flange, said latter flange having an annular slit therein the depth of which is about one-quarter of the wave-length of the electromagnetic waves transmitted through the window.

2. A magnetron comprising a hollow anode block having a plurality of fin-shaped anode segments defining an axis of the magnetron and a plurality of resonant cavities around said axis, said block having an outwardly flaring bore defining a conical wave-guide connected to one of said resonant cavities by an aperture in said anode block, a hollow electrically conducting cylinder closed at one end by a flange having a window therein for the transmission of electromagnetic waves and secured at the other end to a shoulder on said anode block, said electrically conducting cylinder surrounding said conical wave-guide and defining with said anode block a slit between the wall of said wave-guide and the electrically conducting cylinder, a pair of segments lying in a plane normal to said axis extending in said wave-guide from said aperture toward said window and a rectangular wave-guide having a flange at one end secured to the flange at the end of the electrically conducting cylinder, said flange at the end of said rectangular wave-guide having an annular slit the depth of which is one-quarter of a wave-length of the electromagnetic waves transmitted through said window.
